UNITED STATES PATENT OFFICE.

LARS R. JORGENSEN, OF BERKELEY, CALIFORNIA, ASSIGNOR, BY MESNE ASSIGNMENTS, TO CONSTANT ANGLE ARCH DAM COMPANY, OF SAN FRANCISCO, CALIFORNIA, A CORPORATION OF CALIFORNIA.

DAM CONSTRUCTION.

Application filed February 4, 1924. Serial No. 690,375.

This invention relates to a dam structure, and particularly to concrete dams of the arch type.

An arch dam can be designed either with 5 the up-stream and down-stream face struck from the same center at all elevations or from the same centers at various horizontal elevations.

When the water load acts on an arch dam 10 the arch deforms, due to the strain developed in the material. When the crown of the arch is forced in a down-stream direction by the water pressure principally and also by shrinkage due to setting, drop 15 in temperature and rib shortening, bending stresses are set up in the arch besides the axial compression. These bending stresses for an arch having concentric up and down-stream faces are a maximum at the abutments.

In order to make an economical arch dam 20 design or structure, it is therefore necessary to deviate from the usual method of dam construction having concentric circular faces 25 and to space the faces unequally from one another, at least for a part of the dam body, so that at points of maximum bending moments the distance between the faces or, in other words, the dam thickness, will be 30 greatest.

The object, therefore, of the present invention is to so construct a dam of the character described that it is equally safe and economical in all its parts, which practically 35 means that each section should be so proportioned that the maximum allowable fiber stress at the crown shall be equal to that at the abutments or as nearly so as possible, and that the shear and cantilever stresses 40 towards the bottom and at the bottom shall be held closely within safe limits.

The method of reinforcing the dam and the detail construction thereof are more fully described in the appended specification and drawings, in which—

Fig. 1 is a plan view of an arch dam 45 across a canyon where the subtended angle is kept as near constant and as near 120° as possible; this view also showing the contour lines from the bottom of the dam to the crest thereof, the contour lines being indicated by the numerals 0—0, 20—20, 45—45, 50 70—70, 90—90 and 100—100, 0—0 representing the contour lines at the crest of the dam,

and 100—100 representing the contour lines 55 of the river or bottom of the dam.

Fig. 2 is a central vertical cross-section taken on line 2—2, Fig. 1.

Fig. 3 is a horizontal plan section taken 60 on line 3—3, Fig. 2.

Fig. 4 is a horizontal plan cross-section taken on line 4—4, Fig. 2.

Fig. 5 is a horizontal plan cross-section taken on line 5—5, Fig. 2.

An arch dam of the character here illustrated 65 can be designed either with the up-stream or down-stream faces struck from the same center at all elevations or from the same centers at various horizontal elevations.

When the water load acts on an arch dam 70 of this character the arch deforms, due to the strain developed in the material; that is, when the crown of the arch is forced in a down-stream direction by the water pressure, and also by shrinkage due to setting, drop 75 in temperature and rib shortening, bending stresses are set up in the arch besides the axial compression. Applying the ordinary bending formulas for loaded 80 arches to any particular arch dam, discloses the fact that the bending moment is a maximum at the abutments and gradually diminishes to zero at the points of contraflexure, which points are located a distance out from 85 each abutment very close to 21% of the length of the middle arc.

A maximum unit compression is therefore introduced in the material on the down-stream side at the abutments, and a minimum 90 unit compression on the upstream side of the dam at the abutments; this minimum unit compression is often actual tension.

From the abutments towards the two 95 points of contraflexure this difference in unit loading is gradually disappearing, and does disappear entirely at the points of contraflexure, where the average compression is much less than the maximum at the abutments.

It can, therefore, be readily seen that for 100 economy's sake, extra material should be added only where the stresses are concentrated, and that the thickness added should be in proportion to this concentration. As 105 the increase of unit stress above the average along the down-stream face ceases a distance of 21% of the length of the arc from each

abutment, there would be no object in adding material beyond this point. In fact, it is proper to stop the addition of material at a distance of approximately 18% of the length of the arc out from the abutments. At these points the addition should be zero, increasing approximately uniformly to a maximum at the abutments. The amount to be added (the thickness) is dictated by 10 the maximum allowable stress which is assumed before starting on the design.

Near and at the bottom of an arch dam, arch action is very incomplete and the load is therefore taken up by cantilever and shear 15 action. The cantilever here supports the greatest load in the middle between the abutments where the height of the dam is the greatest, and the deflection of the cantilever in a down-stream direction the greatest 20 with the reservoir full. Hence, greater thickness is often required in the middle of the dam than at the abutments near the bottom.

On the other hand, dam sites may be found 25 where arch action even close to the bottom would be considerable and cantilever action not so great. This would require greater thickness at the abutments than in the middle, due to the predomination of bending in 30 a horizontal plane over that in a vertical plane. The combination of cantilever and arch action which constitutes the actual resultant load carrier will on such sites therefore require the lower part of the dam to 35 have concentric up-and-down-stream faces in order to have the material stressed to a point where the factor of safety for shear and for compression is as near equal as it can be made.

40 It is for this reason that dam sites can be found where it would be most economical to start the dam with concentric up-and-down-stream faces at the bottom and gradually increase the thickness at and towards the 45 abutments at higher elevations in order to take care of the increased horizontal bending moment at these higher elevations. This thickening at and towards the abutments should preferably be taken care of on the 50 down-stream side in order to keep the middle radius small and the subtended angle as large as possible. Some material may, however, be added on the upstream side, as shown in my former Patent No. 1,087,662 at 55 the point *f*, as shown in Fig. 2. The additional material thus applied should have a maximum thickness at the abutments and should then diminish to zero towards the point of contra-flexure. For instance, as 60 illustrated at A and B in Fig. 4.

Other dam sites may sometimes be found, as mentioned above where calculation would show that it would be most economical to shape the bottom of the dam so that it would 65 be thicker in the middle than at the abut-

ments. (See, for instance, the construction of the dam shown in Fig. 3 and the structure shown in my Patent No. 1,087,662.) The up-stream face of the dam would in that case be kept substantially circular in a horizontal plane or as nearly so as possible. Towards higher elevations the two faces might be required to be concentric in a certain zone. Above this zone the dam sections might have to be thickened between the 75 abutments and points of contra-flexure with a maximum addition at the abutment tapering to nothing toward the points of contra-flexure, as previously referred to in Fig. 4, and in the upper zone towards the crest of 80 the dam the up-and-down-stream faces may again be required to be made concentric for the whole horizontal arch as illustrated in Fig. 5. The material in this zone can not be highly stressed for practical reasons. 85

Different dam sites may require different combinations. In each case the moments and their resulting stresses in the material would have to be calculated at a sufficient 90 number of elevations to admit of designing a cross-section for the particular site, bearing in mind that the most economical arch dam subtends a constant angle at 120° across the canyon at all elevations.

If the canyon is U-shaped in cross-section, 95 then the up-stream radius will be constant from top to bottom, but if shaped more like a V then the radius will have to diminish in length from the top of the dam to the foundation for economy sake. Besides that, 100 the centers for the individual arches at different elevations may have to be offset relative to one another in order to obtain an 105 architecturally practical structure. In a V-shaped canyon the rule also holds that the angle subtended by the arch should be as 110 near 120° at all elevations as possible.

At most sites it will not be found possible 115 to keep the subtended angle as large as 120° towards the lower elevations, but the rule is nevertheless to attempt to do so by changing the length of the radii corresponding to the different spans at different elevations.

Having thus described my invention, what I claim and desire to secure by Letters 115 Patent is—

1. An arch dam divided into an upper, a middle and a lower zone and comprising superposed integral arch-shaped elements of various thicknesses in different zones and at 120 various elevations, the radial thickness of the arch-shaped elements being the same in any horizontal plane in the upper zone near the crest, the radial thicknesses of the arch-shaped elements in the middle zone being the 125 same in any horizontal plane to a location just past the points of contra-flexure, from where the thickness gradually increases to a maximum at the abutments, and the radial thickness of the arch-shaped elements in the 130

bottom zone being of maximum thickness in the middle and a minimum at or towards the abutments.

2. An arch dam divided into an upper, a middle and a lower zone and comprising superposed integral arch-shaped elements of varying radii, the center of curvature of such elements being out of vertical alignment, the radial thickness of the arch-shaped elements being the same in any horizontal plane in the upper zone near the crest, the radial thickness of the arch-shaped elements in the middle zone being the same in any horizontal plane to a location just past the points of contra-flexure, from where the thickness gradually increases to a maximum at the abutments for a distance of about 15 to 20 per cent of the length of the arch, and the radial thickness of the arch-shaped elements in the bottom zone having a maximum thickness in the middle and a minimum at or towards the abutments.

3. An arch dam divided into an upper, a middle and a lower zone and comprising superposed integral arch-shaped elements of various thicknesses in different zones and at various elevations, the radial thickness of the arch-shaped elements being the same in any horizontal plane in the upper zone near the crest, the radial thickness of the arch-shaped elements in the middle zone being the same in any horizontal plane to a location just past the points of contra-flexure, from where the thickness is gradually increased to a maximum at the abutments, and the radial thickness of the arch-shaped elements in the bottom zone being the same in any horizontal plane.

4. An arch dam divided into an upper, a middle and a lower zone and comprising superposed integral arch-shaped elements of varying radii, the center of curvature of

such elements being out of vertical alignment and the radial thickness of the arch-shaped elements being the same in any horizontal plane in the upper zone near the crest, the radial thickness of the arch-shaped elements in the middle zone being the same in any horizontal plane to a location just past the points of contra-flexure, from where the thickness is gradually increased to a maximum at the abutments, said gradual increase in thickness taking place for a distance of about 15 to 20 per cent of the length of the arch, and the radial thickness of the arch-shaped elements in the lower zone being the same in any horizontal plane.

5. An arch dam divided into an upper, a middle and a lower zone and comprising superposed integral arch-shaped elements of various thicknesses in different zones, the radial thickness of the arch-shaped elements being the same in any horizontal plane in the upper zone, near the crest, and in the middle zone the thickness of the arch decreasing gradually from the abutments for a distance of 15 to 20 per cent of the length of the arch towards the points of contra-flexure.

6. An arch dam divided into an upper, a middle and a lower zone and comprising superposed integral arch-shaped elements of various radii, the center of curvature of such elements being out of vertical alignment and the radial thickness of the arch-shaped elements being the same in any horizontal plane in the upper zone, near the crest, and in the middle zone the thickness of the arch decreasing gradually from the abutments for a distance of 15 to 20 per cent of the length of the arch towards the points of contra-flexure.
